MEASURED SERVICE TELEPHONE SYSTEM

Herbert Töpfer, Berlin-Siemensstadt, Germany,
assignor to Siemens & Halske Aktiengesellschaft, Wernerwerk, Siemensstadt, near Berlin, Germany

Application January 30, 1937, Serial No. 123,227
In Germany February 14, 1936

6 Claims. (Cl. 179—7.1)

The present invention relates to a circuit arrangement for metering variously related calls in remote communication systems and more especially for telephone systems in which the metering is registered, in which the reckoning of the fee by influencing the meter of the calling subscriber's line only takes place after a definite time for example at the end of the call.

The invention aims at simplifying the devices for determining the amount of the fee in accordance with the time and zone of the call relative to the known arrangements of this kind and this is achieved in that a special group of contacts is provided for each traffic zone in the contact bank or banks of the assessor containing a number of switching positions corresponding to the greatest number of metering impulses which have to be transmitted for a call in the desired call zone.

In the known arrangements of this kind it is necessary to provide a zone switch, a time switch and an assessor. The present invention obviates the necessity of providing a separate time switch. On account of the construction of the contact bank or banks of the assessor according to the invention it is possible to use the devices serving to characterize and register the zone as a time switch. Furthermore the invention has the advantage that it is particularly applicable in systems with a large number of traffic directions and works even in these systems with complete efficiency.

In addition to the foregoing, the present invention is concerned with a circuit arrangement in which after the number of metering impulses to be transmitted has been characterized these impulses are transmitted by the aid of an assessor. In known arrangements of this kind the characterizing of the number of metering impulses to be transmitted is effected in that a particular contact in the contact bank of the assessor is characterized by the connection to it of potential. In these arrangements when the time comes for effecting the metering the assessor is advanced in steps until it reaches the contact which has been characterized. Thereupon a relay serving to terminate the metering is energized over this contact.

These known arrangements have the disadvantage that when through the breaking of a cable or as a result of some other fault the potential is not applied so-called "prolonged metering" takes place, i. e., the assessor is operated continuously since it finds no metering cut-off potential and consequently transmits metering impulses continuously. This objection is avoided by the

present invention in that a number of contacts in the contact bank of the assessor equal to the number of impulses which have to be transmitted to the calling subscriber's meter for the call established are connected to potential by switching devices (zone switch, time switch) determining the amount of the fee to be charged.

One embodiment of the invention is represented in the drawings.

Figs. 1 and 2 show the various circuits of a repeater when taken together. Fig. 2 should be placed at the right of Fig. 1.

The arrangement shown represents a repeater of which the following are the important parts.

(1) A rotary switch DG

This rotary switch possesses four wipers and is set by the first impulse train transmitted from the calling station and operating on the repeater for the purpose of determining the traffic direction. The zone of the call is characterized over wiper g_1 . The rotary switch is used for determining the duration of the call after it has functioned as a zone switch and the zone characterization has been taken over by another switching device. This function of determining the duration of the call is exercised by wiper g_2 which is specially constructed. Wiper g_2 consists of a contact segment by the aid of which it is possible to connect together all the contacts over which the segment g_2 passes in the course of its motion. If a conversation lasts for example for 8 minutes and the contact segment g_2 is advanced one step for each minute all the contacts 1—8 are connected together and are maintained connected by the contact segment.

(2) The motor switch DM with its two motor windings I and II

This motor switch has ten wipers of which wipers m_1 to m_8 likewise serve for zone characterizing. The mode of operation of the motor switch DM for characterizing the zone is that the motor switch is advanced by the second characterizing digit transmitted by the calling subscriber in large steps and is advanced by the third characterizing digit in smaller steps. The wipers m_1 to m_8 are disposed in series with the wiper g_1 of the rotary switch DG. A particular zone point Z_{0I} to Z_{0VIII} is characterized over wiper g_1 and one of the wipers m_1 to m_8 . The zone thus characterized is taken over by another switching device as described above so that the motor switch DM is released for other purposes. It is brought under the influence of an impulse sender

which transmits impulses at intervals, for example ten seconds and in turn influences the rotary switch DG arranged for determining large intervals of time, for example minutes.

5 (3) *The motor switch DA with its two motor windings I and II*

This motor switch serves as a zone assessor for transmitting the meter impulses at the end of a call. After the characterizing of a zone by the rotary switch DG and the motor switch DM the assessor DA hunts for the zone contact which has been characterized and remains on this contact until the termination of the call. When the time 10 comes for metering, i. e., when the calling station has given the clearing signal the motor switch DA is started up from the point on which it has been set and is advanced to a contact characterized by wiper *g2* of the rotary switch DG now serving 15 as a time switch, thereby transmitting one metering impulse for each step.

(4) *The control switch DS*

25 The control switch DS supervises the mode of operation of the switching devices which have been mentioned and determines the time at which the individual switching operations are carried out. It possesses 16 contacts. The contacts which are closed in the individual positions are 30 designated by *St1*—*St16*. The manner of operation of the control switch is known per se. Its application for the present purpose may be seen from the detailed description.

35 The mode of operation of the repeater which is here represented will now be described in detail.

It will be assumed that the repeater is disposed beyond the first group selector. When the preceding group selector is set on the repeater shown 40 the latter is seized over the *c*-lead. The control switch stands in its starting position in which all the contacts designated by *St1* are closed. Thus the following circuit is completed for relay C in the repeater: earth in the preceding group 45 selector, lead *c*, a contact which is closed in position *St1* of the control switch, winding II of relay C, battery and earth. Relay C closes contact *70c* and thereby completes the following circuit for the winding of relay S: earth, contact 50 *70c*, control switch contact *St1*, winding of relay S, resistance *Wi12*, battery and earth. Relay S locks up in the following circuit which is independent of the setting of the control switch: earth, contact *70c*, *69s*, winding of relay S, resistance *Wi12*, battery and earth. At the same 55 time the following circuit is completed for the stepping relay F of the control switch: earth, contact *76c*, resistance *Wi11*, control switch contact *St1*, winding I of relay F, resistance *Wi9*, battery and earth. Relay F energizes in this 60 circuit and closes the following circuit for magnet DS of the control switch: earth, battery, magnet DS, contact *67f*, resistance *Wi10* and earth. By the closing of contacts *68ds* winding I of relay F is short-circuited so that this relay 65 releases and at contact *67f* breaks the circuit for magnet DS. The control switch is thus stepped from position 1 to position 2 so that all the contacts designated by *St2* are closed.

70 Winding I of relay C is operated in the seizing circuit this relay having previously been short-circuited by the control switch contact *St1*.

The repeater is now ready to receive the impulse trains transmitted by the calling station.

75 Relay S closed contact *3s* and thereby connected

winding I of the impulse receiving relay A to the upper speaking lead. The impulses transmitted by the calling station operate relay A intermittently over the following path: earth in the preceding first group selector, impulse contact in 5 the group selector, upper speaking lead *a*, contacts *1b*, *3s*, winding I of relay A, battery and earth. The speaking leads of the repeater passing to the following connecting devices are switched through by relay S at contacts *16s* and 10 *17s*, so that the impulses transmitted to the succeeding connecting devices from the calling station are transmitted to the succeeding connecting devices over the following path: earth, contact *15b*, contact *14a* operated intermittently, the 15 upper speaking lead, contact *16s* and further to the succeeding connecting devices. Relay A also intermittently operates its contact *51a* so that magnet DG of the rotary switch receives impulses over the following path: earth, contact *51a*, winding III of the relay V, control switch contact *St2*, magnet DG, battery and earth. Wipers *g1* to 20 *g4* of the rotary switch DG are accordingly brought to a particular position corresponding to the impulse trains transmitted. In the above 25 circuit for magnet DG is arranged also winding III of relay V which relay also energizes. This relay at contact *10v* short-circuits its winding I so that it operates as a slow-to-release relay and bridges over the gaps between the individual impulses of the impulse train. Thus relay V only releases some time after the last impulse is transmitted. Through the opening of contact *13v* the upper speaking lead is cut off during the 30 transmission of the individual impulses in order to avoid disturbance from the side of the calling subscriber. At the end of the impulse train the following circuit is established for the stepping relay F of the control switch: earth, contacts 35 *52a*, *73v*, wiper *g4* of the rotary switch DG in the 40 operated position, control switch contact *St2*, winding I of relay F, resistance *Wi9*, battery, earth. Relay F causes the control switch to advance in the manner already described, so that it steps to position 3. When the calling station 45 transmits the next impulse train, relay A is again influenced over its winding I in the same circuit as in the case of the first impulse train.

By the closing of contact *9a* the following circuit is set up for relay V: earth, contacts *11c*, *9a*, 50 control switch contact *St3*, windings I and II of relay V, battery and earth. Relay V energizes in this circuit and again holds its contacts operated throughout the impulse train. At the same time, as in the case of the first impulse train, the following circuit is completed for relay Y: earth, contacts *11c*, *9a*, winding I of relay Y, battery, earth. Relay Y energizes intermittently in this circuit. Special switching operations which are 55 important in connection with the arrangement to be described are not initiated by relay Y at this moment. It will merely be mentioned that relay Y serves to release the seized repeater in the event of the subscriber failing to transmit any 60 impulse train for a prolonged period. In addition, it serves the further purpose of preventing the metering operation from being cut short, which may happen by the calling subscriber preventing the normal setting of the devices serving 65 to determine the number of metering impulses to be transmitted by displacing his dial switch a number of times when the calling subscriber replies.

70 Through the intermittent opening and closing 75

of contacts 55a and 57a, the impulses of the second impulse train operating on the repeater are transmitted to the motor switch DM. Over the control switch contact St3 and contact 50v, earth potential is applied to the cam contact 47mk of the motor switch. Winding II of the motor is accordingly operated over: earth, contact 50v, control switch contact St3, cam contact 41mk operated by the motor, winding II of the motor, battery, earth. The motor is, however, not able to start up at once since winding I of the motor is also operated and thus no turning moment can be exerted on the motor. The winding I of the motor is operated over the following circuit: earth, battery, winding I of the motor, control switch contact St3, contact 56a, wiper m9 of the motor switch DM in the starting position, cam contact 41mk, control switch contact St3, contact 50v, earth. The motor switch can only advance its wipers when, after the first impulse has terminated, contact 56a has opened and contact 57a accordingly closed. The wipers are advanced by only one step until wiper m9 rests on contact 0. In this position, both windings of the motor are operated over:

(1) Earth, battery, winding I of the motor, control switch contact St3, contact 51a, rest contact 0, wiper m9 of the motor switch DM, cam contact 47mk, control switch contact St3, contact 50n, earth, and

(2) Earth, battery, winding II of the motor, cam contact $47mk$, control switch contact St3, contact $50v$, earth.

35 Alternatively if the cam contact 46mk of the motor were closed, both windings of the motor would be connected up as may be seen directly from the drawings. When now the second impulse of the impulse train is received, contact 51a is again opened, and contact 56a closed. The motor switch DM can then advance its wipers automatically so long as contact 51a is open, until they reach contact 7, since then both the windings of the motor are operated again at the same time, winding I over the circuit: earth, battery, winding I of the motor, control switch contact St3, contacts 56a, 55a, contact 7, wiper m9 of the motor switch, motor contact 47mk, control switch contact St3, contact 50v and 50 earth, and winding II of the motor in a manner which may be easily seen from the drawings. When, after the end of the second impulse of the train, contact 51a is again closed the switch DM can advance its wipers to the 10th contact. 55 When this contact is reached by wiper m9, both windings of the motor are operated again simultaneously so that the motor switch remains set and can only be advanced when the next impulse is received.

60 In this way the wipers of the motor switch DM are advanced by 10 steps for each impulse received. Thus at the end of the impulse train, wiper m_9 stands on a main resting position, thus for example, on contact 10, 20, 30, 40, etc.

65 Shortly after the termination of the last impulse and after the protracted opening of contact 9a, relay V releases. The control switch is advanced from position 3 to position 4, the stepping relay F being energized over the following path: earth, contact 52a, 73v, rotary off-normal contact 74wm of the motor switch DM which is closed as soon as the motor switch leaves its rest position, control switch contact 75 St3, winding of relay F, resistance Wi9, battery,

earth. The control switch is advanced into position 4 in the manner described.

The next impulse train transmitted by the calling station again influences winding I of relay A in the manner described. The impulses are repeated to the motor switch DM by the intermittent closing and opening of contacts 51a and 52a and the motor switch is now advanced only one step for each opening and closing of the contact. The first time that contacts 51a close the following circuit is set up: earth, contact 51a, winding III of relay V, control switch contact St4, cam contact 47mk, winding II of the motor, battery, earth. In this circuit relay V energizes and again maintains its contacts operated throughout the impulse train. In addition winding II of the motor is energized so that the associated contact 49m2 is closed and now both windings of the motor are operated over:

(1) Earth, battery, winding I of the motor, cam contact $46mk$, control switch contact $St4$, winding III of the relay V, contact $51a$, earth, and

(2) Earth, battery, winding II of the motor, control switch contact 4, contact 49m2 controlled by the winding II of the motor and as before to earth

By the opening of contact 51a earth is disconnected from both windings of the motor. Thus the motor switch takes one step for each impulse transmitted by the calling subscriber. Wipers m_1 to m_9 of the motor switch DM are thus set on a definite contact. So long as relay V is still energized, the following circuit is established for winding I of relay T: earth, control switch contact St4, contact 25v, winding of relay T, resistance W13, battery, earth. When at the end of the impulse train relay V releases, the circuit for relay T is broken again but a fresh circuit is completed for this relay at contact 26v: earth, control-switch-contact St4, contact 26v, wiper g1 of the rotary switch DG, a particular contact in the contact bank of this wiper, one of the wipers m_1 to m_8 of the motor switch DM, a contact in the bank traversed by this wiper, one of the zone leads Z01 to Z0VII, winding of relay T, resistance W13, battery and earth. Thus relay T remains energized so that the following circuit is set up for the stepping relay F of the control switch DS: earth, contact 52a, 73v, 78t, control switch contact St4, winding of relay F, resistance W19, battery, earth. The control switch thus proceeds from position 4 to position 5. In position 5 also relay T is maintained energized, namely over earth which is connected at wiper g1 of the rotary switch DG over control switch contact St5. Since relay T remains energized contact 78t also remains operated so that in position 5 of the control switch the circuit just set out for the stepping relay F of the control switch DS is established. Thus the control switch proceeds from position 5 to position 6.

Relay T is the so-called "zone testing relay." It tests as to whether the numerical impulse trains transmitted by the calling station correspond in their combination to a zone characteristic. It has been assumed that the impulse trains transmitted do correspond to a zone characteristic. If, however, this is not the case, i. e., if the calling subscriber transmits characterizing digits whose combination does not correspond to any zone characteristic, the setting of the wiper g_1 of rotary switch DG and the connected wiper of

the motor switch DM is such that no circuit can be set up over these wipers for relay T. Thus after relay V has released and contact 25v has opened and contact 26v has closed no circuit obtains for relay T over the control switch contact St4. Accordingly relay T releases before the control switch has been advanced from position 5 to position 6. Since contact 78t is now open the control switch in position 5 receives no fresh advancing impulse but remains in the position in which it has been set. Accordingly the winding of relay S shown in the top right-hand corner of the drawing is short-circuited over control switch contact St5. The locking circuit over contact 69s is thus opened so that relay S falls back. The succeeding connecting devices are released by the opening of contacts 16s, 17s, and 18s. The release of the repeater with its associated devices can also take place in any known manner.

It will now be assumed that the characterizing digits transmitted by the calling station correspond in their combination to a zone characteristic. It has already been mentioned that the control-switch ST in this case is advanced from control switch position 5 to control switch position 6. It may further be mentioned that since the control switch remains in position 5 only a very short time and the short-circuit for relay S over control switch contact St5 only obtains for a very short time, relay S cannot release.

The calling subscriber now transmits the other numerical impulse trains which are repeated by contact 14a to the succeeding connecting devices and thus establishes the connection to the desired station. The devices in the repeater are not influenced by these impulse trains.

It will be assumed that the connection to the desired station has been established and that the called party has replied. In this case battery is applied to the lower speaking lead in a succeeding connecting device. The following circuit is established: earth, battery in the succeeding connecting device, lower speaking lead, contacts 17s, 22y, control switch contact St6, winding I of relay B, contacts 23b, 24f, earth. In this circuit relay B energizes and opens contact 23b and thereby removes the short-circuit about winding II of relay F. Relay F energizes, opens a further point in its short-circuit at contact 24f and closes contacts 67f thereby switching on the magnet DS of the control switch. The control switch is thus advanced from position 6 to position 7. The control switch contact St6 is thus opened so that the above-mentioned circuit for relays B and F is again broken. These two relays release.

In position 7 of the control switch earth is connected to cam contacts 62ak and 63ak of the motor switch DA: earth, contact 59c, control switch contact St7, cam contact 63ak and 62ak, winding II of the motor and winding I of the motor, battery, earth. The motor switch operates automatically (by self-interruption) and moves its wipers da1 to da4 over the contact banks. The stepping of the motor switch continues until one of the wipers of this switch has found a zone contact Z0I to Z0VII, which is connected to earth over one of the wipers m1 to m8 and wiper g1. Assuming that a connection has been established in zone IV during the day time, the following circuit is set up: earth, battery, winding of relay P, control switch contact St7, contacts 38u, 36n, wiper da1 of the motor switch DA, zone contact Z0IV, wiper m3, contact 3, wiper g1, control switch contact St1, earth. In this circuit the highly

sensitive and rapidly testing relay P energizes and by closing its contact 61p simultaneously operates both windings of switch DA so that the switch temporarily comes to rest. The following circuits are set up for the two windings of the motor: earth, contact 59c, control-switch contact St7, then on the one hand over contacts 63ak and 61p to winding I and on the other hand over cam contact 63ak and winding II and then battery, earth. By the closing of contact 85p the following circuit is completed for the advancing relay F of the control switch: earth, contact 85p, control switch contact St7, winding I of relay F, Wi9, battery, earth. The control switch is advanced in the manner previously described. It proceeds thus to position 8. In position 8 of the control switch the following circuit is set up: earth, control switch contact St8, wiper g3 of the rotary switch DG in the working position, contact 4dg of magnet DG, winding I of relay A, battery, earth. In this circuit relay A energizes, closes its contact 51a and thereby completes the following circuit for magnet DG: earth, contact 51a, control switch contact St8, magnet DG, battery, earth. The rotary switch DG is thus advanced one step. Contact 4dg of magnet DG is broken and hence the above circuit for relay A is also broken. Relay A accordingly releases and opens its contact 51a again and accordingly breaks the circuit for magnet DG. Contact 4dg is again closed and relay A energized, which by closing contact 51a operates magnet DG again. The reciprocal play between magnet DG and relay A is continued until the rotary switch DG reaches its normal position in which a circuit can no longer be established for relay A. The control switch is advanced from position 8 to position 9 due to the following circuit being established for the advancing relay F of the control switch: earth, contacts 52a, 73v, wiper g4 of the rotary switch DG in the zero position, control switch contact St8, winding I of relay F, resistance Wi9, battery, earth.

The motor switch DM is now advanced into its rest position, earth being applied to the cam contacts 46mk and 47mk of the switch over the control switch contact 9. The motor switch is accordingly advanced automatically (by self-interruption) until it has reached its normal position. When this is the case the rotary off-normal contact 75wm is closed and the following circuit is established for the advancing relay F of the control switch: earth, contacts 52a, 73v, rotary off normal contact 75wm, control switch contact 9, winding I of relay F, resistance Wi9, battery, earth. The control switch passes from position 9 to position 10 where it remains throughout the duration of the call.

The two switches DG and DM, which are now in the rest position and whose function of characterizing the zone has been taken over by the assessor DA can now be dispensed with as regards this purpose. They are now, after the called subscriber has replied, used to determine the duration of the call.

The following supplementary description will be given: In position 8 of the control switch, B is energized in the following circuit: earth, contact 11c, control switch contact St8, winding II of relay B, winding II of relay Y, battery, earth. Relay B thus applies earth to the upper speaking lead only when the control switch reaches position 8, the earth being applied over contact 2b and winding I of relay E. When the control switch passes to position 9 the circuit for relay 75

B is maintained and in addition relay B1 energizes: earth, contact 11c, control switch contact St9, winding of relay B1, winding II of relay B, winding II of relay Y, battery, earth. Relay Y also energizes. A locking circuit is set up for all three relays over contacts 12b1.

As has already been stated the control switch remains in position 10 during conversation. After relay B1 has energized a ten second switch 10 is connected to winding II of relay A. Relay A accordingly receives impulses every ten seconds over the following path: tens-seconds switch, contacts 88b1, 87e, rotary off normal contact 96wa of the assessor DA (closed when the assessor 15 is off normal), winding II of relay A, battery, earth. The ten seconds impulses are transmitted to the motor switch DM over control switch contact St10 by the closing of contact 51a. The motor switch DM is thus displaced by one step 20 every ten seconds. By suitably wiring the contact bank of the motor switch DM the switch DG is arranged to be influenced only in particular 25 positions of the motor switch DM. The motor switch DM thus totals up the tens-seconds impulses and influences the rotary switch DG at larger intervals of time. The wiring of the contact bank of motor switch DM is so arranged that for the first three minutes of the call a single advancement of the rotary switch DG takes place, 30 after the lapse of the free period, i. e., that period which is appointed to enable the calling party to ascertain that the correct call has been set up, only a small charge being made if the clearing signal is given within the period. After the first 35 three minutes the switch DG is advanced one step per minute.

On each energization of relay A through the ten second impulses the motor switch DM is operated over the following path: earth, contact 51a, 40 control switch contact St10, cam contacts 46mk or 47mk, motor windings I and II, battery and earth. Over motor contacts 48m1 and 49m2 and control switch contacts St10 both windings of motor DM are connected in the same way as in 45 control switch position 4 in which the motor switch is advanced in steps (external control). Thus the motor switch is stepped on each opening and closing of contact 51a. Wiper m9 of this switch is thus advanced by the first ten seconds 50 impulse to position 0, by the second to position 1, and the third to position 2. Thus in approximately 20 to 30 seconds wiper m9 is brought to contact 2 and sets up the following circuit: earth, contact 51a, control switch contact St10, cam 55 contact 47mk of the motor switch and then on the one hand to winding II of the motor and battery to earth and on the other hand over wiper m9, contact 2, control switch contact St10, magnet DG, battery and earth. Thus the first advancement of the rotary switch DG occurs 60 when contact 51a is closed after wiper m9 has been set on contact 2. Wiper g2 passes into its first switching position and remains in this position for three minutes as will be further described 65 below.

As may be seen from the drawings, contact 2, in the contact bank of motor switch DM which is traversed by wiper m9, on which contact the wiper m9 is set at the moment, is connected to a strip. On reaching any of the switch positions which are connected over this strip the switch DG is advanced as is its wiper G2. The switch DG is stepped forward as may be seen from the drawings when wiper m9 reaches contact 18, i. e., after conversation has lasted for three minutes. The next

advancement takes place when wiper m9 passes to contact 4', i. e., after the conversation has lasted for four minutes. The switch DG is now advanced one step per minute. The stepping of the switch DG continues in this way until the 5 termination of the call.

When the calling subscriber replaces his receiver at the end of the call battery is connected to the upper speaking lead in the preceding group selector. The following circuit is set up for relay 10 E: battery potential in the preceding group selector, the upper speaking lead, contact 2b, winding I of relay E and earth. Relay E energizes in this circuit, closes its contact 83e, and thereby completes the following circuit for the stepping 15 relay of the control switch: earth, contact 83e, control switch contact St10, winding I of relay F, resistance Wi9, battery and earth. The control switch is thus advanced to position 11. In position 11 of the control switch, testing takes place 20 as to whether the metering impulse receiving relay in the first group selector which is connected to earth and the lower speaking lead has been duly connected to this lead. If this is closed the following circuit is set up: earth, metering relay 25 in the preceding group selector, lower speaking lead, control switch contact St11, resistance Wi7, winding I of relay S1, battery and earth. Relay S1 energizes and closes its contact 80st and thereby completes the following circuit for the stepping 30 relay F of the control switch: earth, contact 80st, control switch contact St11, winding I of relay F, resistance Wi9, battery and earth. The control switch is thus advanced to position 12. Relay S1 35 releases again. In position 12 of the control 35 switch winding I of relay E is short circuited. The relay does not release, however, its energization being maintained in the manner which may be seen from the following description. Through the opening of contact 87e, the ten seconds switch 40 was disconnected from the winding II of relay A. This winding is immediately reoperated over: earth, contact 89c, control switch contact St12, contact 86s1, winding II of relay A, battery and earth. Relay A closes contact 51a and thereby 45 applies earth for advancing the motor switch of the assessor. Earth, contact 51a, winding III of relay V, control switch contact St12, cam contact 62ak and 63ak of the motor switch DA, motor 50 windings I or II, battery and earth. By closing contacts 64a and 65a (contacts 60e and 66e are also closed) the two windings of the motor are connected up so that the motor switch can only advance step by step on each application of earth potential to contact 51a. In the above circuit 55 relay V also energized and closed contact 58v and thereby set up the following circuit for relay S1: earth, contacts 59v, 58e, winding II of relay S1, battery and earth. Relay V has a definite delay feature so that relay S1 remains energized for a definite time. The result of this is that relay S is caused to release since the following short-circuit is established for the winding of this relay: earth, battery, resistance Wi12, contact 60 72s1, control switch contact St12, contact 78c, and earth. Relay S thus releases and breaks the leads passing to the succeeding connecting devices. These are thus released independently of the transmission of the metering impulses. The motor switch DA of the assessor is thus stepped 70 by the first closing of contact 51a from the zone contact on which it is set. Simultaneously by the application of battery to the lower speaking lead metering potential is applied to the lower speaking lead to the preceding group selector and to 75

the metering relay disposed therein, this takes place over the following path: earth, battery, resistance W_{16} , control switch contact S_{12} , contact $6a$, lower speaking lead to the preceding group selector. The meter of the calling station thus receives its first impulse and is advanced one step. Relay S_1 which was operated by contact $50v$ on the first closing of contact $51a$ opens its contacts $86s1$, and thereby breaks the above 5 circuit for relay A. Relay A opens contact $51a$ and thus breaks the circuit of relay V. At contact $50v$ the circuit for relay S_1 is broken and this relay releases. Relay A is reoperated, the next metering impulse is transmitted, the motor switch DA is advanced and relay V is energized 10 by the closing of contact $86s1$. Relay V connects up relay S_1 again and this once more breaks the circuit for relay A. In this way the motor switch DA is advanced and a metering impulse is transmitted 15 at each step.

A somewhat more detailed description must now be given of the construction of the assessor and its contact banks. In the present embodiment the motor switch DA acting as assessor possesses four wipers da_1 to da_4 . The associated contact banks are differently constructed, the difference being in the distribution and multiplying of the contacts. As may be seen from the drawings the contacts of the contact bank traversed by 20 wiper da_1 are divided into five groups of contacts. The first contacts of the individual groups are represented on a larger scale and are designated ZoI to ZoIV. The first group ZoI comprises a single contact which serves at the same time as 25 the normal position for wiper da_1 . This contact position plays no part except in the case of calls in zone I, i. e., for local calls as will be described later.

The contact group associated with the starting 30 contact ZoII comprises 11 contacts excluding the first contact. Of these the first two contacts are connected together. These first two contacts are connected to contacts $1-3$ of wiper g_2 while the remaining contacts $4-12$ of wiper g_2 are individually connected to the corresponding contacts 35 $4-12$ of the contact group ZoII of the assessor.

The contact group starting on contact ZoIII possesses 15 contacts excluding the starting contact and of these the first three are connected 40 together. In addition contacts 5 and 6 , 9 and 10 , 13 and 14 are connected together. The individual sub-groups of contacts are represented by 45 $3'$, $4'$, $5'$, etc., because the contacts or sub-groups of contacts are connected to the corresponding minute contacts of wiper g_2 . The sub-group 3 comprising three contacts is thus connected to contacts $1-3$ of wiper g_2 and the individual contacts $4'$, $6'$, $7'$, $10'$, and $12'$ are connected with the corresponding individual contacts of wiper g_2 50 and similarly the sub-groups $5'$, $8'$, and $11'$ comprising two contacts each are connected to the corresponding individual contacts of wiper g_2 . The contact group starting with contact ZoIV 55 comprises, excluding this contact, 23 contacts. Of these the first five constitute a sub-group and are connected together. They are followed by 9 sub-groups each comprising two interconnected contacts. The first sub-group $3'$ is connected to the individual position $1-3$ of wiper g_2 and the sub-groups $4'-12'$ each comprising two contacts 60 connected together are connected to the corresponding individual contacts of wiper g_2 .

The contact group starting at contact ZoV is 65 subdivided in a different manner which may be

seen from the drawings and is connected to the individual contacts of wiper g_2 .

As may be seen from the drawings five contact groups starting with contacts ZoI to ZoV are arranged in the contact bank traversed by wiper da_1 . These contact groups serve for reckoning the fee chargeable for calls in the traffic directions ZoI to ZoV while the day tariff is being charged.

The contact bank traversed by wiper da_2 contains the contact group starting with contact ZoVI, these serving both for the day and night tariff. The bank traversed by wiper da_3 comprises the contact group corresponding to tariff direction ZoVII and includes two different contact groups for the day and for the night tariff.

The contact bank traversed by wiper da_4 comprises contact groups from ZoI to ZoV which are involved in calls in the tariff directions ZoI to ZoV while the night tariff is obtaining.

Wiper g_2 of the rotary switch DG serving as a time switch is specially constructed in that it is connected to a segment which passes over the contacts of the contact bank with the wiper. Accordingly the said segment connects together all the contacts of the contact bank over which wiper g_2 together with the segment passes in the course of its movement and in dependence upon the duration of the call. To wiper g_2 earth is connected over winding II of relay E and contact 30 $29e$.

Thus if for example the wiper together with the said segment rests on contact 7 that is if a conversation has been in progress for 7 minutes then in the case of calls in zone ZoII the first 35 six contacts are connected to earth potential, in case of calls in zone ZoIII 8 and in the case of calls in zone ZoIV 13.

It should also be noted that the first contact 40 position of wiper g_2 is given the reference $1-3$ because wiper g_2 is only stepped forward from this position when conversation has been in progress for longer than 3 minutes. For this reason also in the individual groups of contacts the first contacts are connected together to an extent corresponding to the zone so as to be able to take 45 into account the 3 minute fee.

It has already been mentioned that winding I of relay E was short-circuited by a control switch contact (closed in position 12). It has 50 also been mentioned that relay E does not release but remains energized. This takes place in the following way. Directly after the control switch leaves position 12 the assessor is displaced one step as described. The wiper of the 55 assessor, for example wiper da_1 , which is set on a zone contact is thus set on a sub-group $3'$ so that the following locking circuit is established: earth, battery, resistance W_{15} , contact $42y$, $38u$, $36n$, wiper da_1 of the motor switch DA, contact 60 position $3'$, contact position $1-3$, wiper segment g_2 , contact $29e$, winding II of relay E and earth. The lapse of time required for this circuit to be set up is bridged by relay E itself which is made slow-to-operate to a certain extent on account 65 of the short-circuit over its winding I through control switch contact S_{12} . This slow-to-release feature also serves to bridge over the intervals taken by the assessor to pass from one contact to another.

The mode of operation will be explained somewhat more clearly by some examples. It will be assumed that a call has been set up in the traffic zone ZoIII and has been in progress for 8 minutes. When the called subscriber replies wiper da_1 is 70

thus set on zone contact $ZoIII$. On the termination of the call wiper $g2$ passes to the 8th contact so that all the contacts 1-8 are connected together. When the time arrives for effecting the metering wiper $da1$ is stepped forward and the circuit for winding II of relay E is maintained until wiper $da1$ reaches a contact over which earth is no longer connected over wiper $g2$. In the example in question this is contact 9. Thus for the call in question 11 metering impulses are transmitted, 4 being sent out for the first 3 minutes, 1 for the 4th minute, two for the 5th minute and one for each of the 6th and 7th minutes and two for the 8th minute.

5 If for example a call is set up in zone 6 and is maintained for 5 minutes then contacts 1-5 are connected together by wiper $g2$. Starting from position $ZoVI$ wiper $da2$ is now advanced in steps and transmits altogether 20 metering impulses, 20 namely 12 impulses for the first 3 minutes and 4 impulses for each of the 4th and 5th minutes. When wiper $da2$ reaches contact position 6 relay E can no longer hold up and metering is thus brought to an end.

25 When at the end of the metering relay E falls back the following circuit is established for the stepping relay F of the control switch: earth, contact $34e$, control switch contact $St12$, winding I of relay F, resistance $Wi9$, battery and earth.

30 The control switch now proceeds to position 13. In position 13 winding II of relay B is short-circuited. Relay B falls back and opens contact 2b thereby removing earth from the upper speaking lead. This forms the criterion for the 35 release of the preceding group selector. Relay C in the repeater then releases. The following circuit is set up: earth, contact $5c$, control switch contact $St13$, wiper $g2$ of the rotary switch DG in the off-normal position, contact $4dg$ of the magnet DG, winding I of relay A, battery and earth.

40 Relay A closes its contact $51a$ and thereby completes the following circuit: earth, contact $51a$, winding III of relay V, control switch contact $St13$, magnet DG, battery and earth. Magnet 45 DG opens its contact $4dg$ and thereby breaks the above circuit for relay A. The circuit for magnet DG is accordingly broken at contact $51a$. Relay A is operated again by the closing of contact $4dg$, and the closing of contact $51a$ 50 operates magnet DG. The reciprocal play between magnet DG and relay A proceeds until the rotary switch DG has reached its normal position in which relay A can no longer be operated. The following circuit is now set up for the stepping 55 relay of the control switch: earth, contact $52a$, $73v$, wiper $g4$, in rest position, control switch contact $St13$, winding I of relay F, resistance $Wi9$, battery and earth. The control switch thus 60 steps from position 13 to position 14. In position 14 earth is applied to the cam contacts $46mk$ and $47mk$ of the motor switch DM; earth, control switch contact $St14$, cam contact $41mk$ of the motor switch DM, motor winding II, battery and earth. The motor switch is thus automatically 65 advanced (by self-interruption). When it reaches the normal position its rotary off normal contact $75wm$ is closed and the following circuit is established: earth, contacts $52a$, $73v$, rotary off normal contact $75wm$, control switch 70 contact $St14$, winding I of relay F, resistance $Wi9$, battery and earth. Relay F causes the control switch to step to position 15. From position 15 the control switch is immediately stepped to position 16 and further to its starting position 75 1: earth, control switch contacts $St15$ and $St16$,

winding I of relay F, resistance $Wi9$, battery and earth.

The repeater together with all its associated devices is once more in the normal position.

In the case of calls which are charged according to the low night tariff naturally different fees from those in the case of calls which are established according to the day tariff must be reckoned with. When contact $30ns$ is closed either by hand or by a clock contact when the moment for switching over to the night tariff arrives the following circuit becomes established when the control switch reaches position 6; earth, contact at the night switch $30NS$, control switch contact $St6$, winding of relay N, battery and earth. By closing contact $31n$ relay N locks up, in a circuit independent of the control switch. The contacts of relay N are accordingly operated during the whole time that the night tariff is chargeable. As may be seen from the drawings, 20 wiper $da1$ of the assessor is disconnected by the opening of contact $36n$ and wiper $da4$, which computes the fee according to the night tariff, is connected up by the closing of contact $37n$. As may at once be seen from the drawings the contact groups for the night tariff in the individual tariff zones are so arranged in proportion to the corresponding contact groups for the day tariff that they comprise fewer contact positions. While the night tariff is chargeable calls which are set up in zones II-V are metered by means of wiper $da4$. In the case of calls of zone VI the contact group connected over contact $34n$ is disconnected and in place of it another contact group is connected up by the closing of contact $35n$. This is also the case for calls in zone VII in which the contact group for reckoning the fee according to the day tariff is disconnected by opening contact $45n$ and is replaced by the corresponding contacts for the night tariff by 40 the closing of contact $44n$.

If a call is set up in zone VI, on testing as to whether digits transmitted correspond as regards their combination to a zone characteristic the following circuit is set up: earth, battery, resistance $Wi8$, winding of relay T, winding I of relay U, wiper $m4$, wiper $g1$ of contact 4, control switch contact $St3$, contact $21v$, and earth. Relay U which serves to connect up particular wipers of the motor switch DA in the same manner as relay R is energized in this circuit and locks up over: earth, contacts $32c$ and $33u$, winding III of relay U, battery and earth. By the opening of contact $38u$ wiper $da1$ which as may be seen from the drawings is only concerned with calls in zones $ZoI-ZoV$ is disconnected and by the closing of contact $39u$ wiper $da2$ which is used for computing the fee for calls in zone VI is connected up.

If the call is set up in zone $ZoVII$ a similar circuit to that described above is set up in which relays U and R are energized, relay U being operated over its winding II and relay R over its winding I. Relay U locks up in the circuit already described while relay R completes the following locking circuit: earth, winding II of relay R, contacts $25r$ and $26u$, resistance $Wi16$, battery and earth. Relay R opens contact $40r$, thereby disconnects wiper $da2$ which is only concerned in calls in zone $ZoVI$, and by closing contact $41r$ switches on wiper $da3$ which is provided 65 for computing fees in the case of calls in zone VII.

In the case of local calls it has to be arranged that no time metering takes place and that for each local call only a single metering impulse 75

is transmitted to the calling subscriber's meter. Wiper *da1* in its rest position stands on zone contact *Zo1*, i. e., on the contact to which earth potential is applied over one of the wipers 5 *m1—m8* and wiper *g1* in the case of local calls. The assessor *DA* is thus not advanced in the case of local calls but remains at rest. For this reason also the rotary off-normal contact *96wa* of this switch remains open so that the 10 seconds impulse sender remains disconnected from winding *II* of relay *A* during these calls. Thus no time 10 metering takes place but merely the transmission of a single impulse on the termination of the call in the known way.

15 15. What is claimed is:

1. In a telephone system having different zones of calling and in which each calling subscriber has a meter operated to assess toll for calls depending upon the zone called, a toll assessing 20 switch, a special group of contacts in the bank of said switch for each zone, each group having as many contacts as required to send the greatest number of metering impulses required to assess toll for that zone, means for selecting a group 25 of said contacts in accordance with the zone called and means for marking the selected groups in accordance with the length of said call, and means for starting the operation of said switch at the termination of the call to send a number 30 of impulses to the calling subscriber's meter, dependent on the contacts marked.
2. In a telephone system having calling lines and means for extending connections therefrom to called lines in different zones, a meter for 35 each calling line, a zone assessing switch having a wiper and special groups of contacts one for each zone, means operated during the extension of a connection for marking one of said groups depending on the zone called, and for then operating the wiper to find the group of contacts, means for thereafter marking the contacts of said marked group before the connection is released, and means for starting the movement of the wiper over the marked group of contacts after 40 the connection is terminated to operate the meter of the calling subscriber in accordance with said last marking.
3. A telephone system as claimed in claim 2,

in which there is also a circuit controller, and means for operating the controller during the call to determine the number of times the meter will be operated by the zone assessing switch in moving over the marked group of contacts. 5

4. In a telephone system having calling lines and means for extending connections therefrom to called lines in different zones, a step by step switch having wipers and a separate set of contacts for each zone, said switch operated during 10 the progress of a call to bring the wipers into association with only one of said sets of contacts, a device operated during the call for placing potential on the contacts of said associated set in accordance with the duration of the call, 15 and means for starting the operation of the switch thereafter to operate the meter of the calling line in accordance with the set of contacts selected and the number of contacts to which potential is connected. 20

5. In a telephone system having calling lines having meters and means for extending connections to called lines in different zones, the provision of an auxiliary zone switch having a set of contacts for each zone, means for determining 25 that a particular set of contacts will be used to operate the meter of the calling line in accordance with the zone thereof, and a switch operated during an established connection for connecting different numbers of the contacts in 30 the different sets to a potential for each interval of time. 35

6. In a telephone system having calling lines and means for extending connections therefrom to called lines in different zones, a step-by-step 40 meter assessing switch having wipers and a separate set of contacts for each zone, a step-by-step switch operated during the extension of a connection to mark a particular set of said contacts in accordance with the zone called, said last switch reoperated during the establishment of a connection to mark a variable number of contacts in the selected set, and means for thereafter operating the assessor switch over the marked contacts to transmit metering impulses 45 in accordance with the marked contacts. 45

HERBERT TÖPFER.
